Primary Examiner — Eric Goodman*Assistant Examiner* — Marie D Fast Horse(74) *Attorney, Agent, or Firm* — Stites & Harbison, PLLC;
David W. Nagle, Jr.(57) **CLAIM**

The ornamental design for a food tray, as shown and described.

DESCRIPTION

FIG. 1 is a perspective view of a food tray in a first orientation and incorporating the design of the present invention; FIG. 2 is a perspective view of the food tray of FIG. 1 in a second orientation;

FIG. 3 is a perspective view of the food tray of FIG. 1 in the first orientation and positioned as a lid of another food container;

FIG. 4 is a perspective view of the food tray of FIG. 1 in the second orientation and positioned as a lid of another food container;

FIG. 5 is a top view of the food tray of FIG. 1;

FIG. 6 is a bottom view of the food tray of FIG. 1;

FIG. 7 is a left side view of the food tray of FIG. 1, and the right side view is identical; and,

FIG. 8 is a front view of the food tray of FIG. 1, and the rear view is identical.

The broken lines in the drawings are included for the purpose of illustrating environmental structure and form no part of the claimed design.

1 Claim, 5 Drawing Sheets---
